UNITED STATES PATENT OFFICE.

GEORGE A. SQUIER, OF CLEVELAND, OHIO.

DESIGN FOR A MOUNTING FOR EYEGLASSES.

SPECIFICATION forming part of Design No. 30,604, dated April 25, 1899.

Application filed March 29, 1899. Serial No. 711,019. Term of patent 7 years.

To all whom it may concern:

Be it known that I, GEORGE A. SQUIER, a citizen of the United States, residing at Cleveland, in the county of Cuyahoga and State of Ohio, have invented and produced a new and original Design in Mountings for Eyeglasses, of which the following is a specification, reference being had to the accompanying drawing, forming, part thereof.

10 In the said drawing I show a perspective elevation of my new design, the leading or material feature of which is found in its unity or oneness of design, forming a symmetry and beauty of design which is attractive to the eye and affords a marked contrast with one which is built up or aggregated out of sundry parts and which unavoidably gives a fragmentary and clumsy effect. Incident to this 15 unitary distinctiveness and attractiveness of the design is its smooth and polished surface *a*, made possible by its singleness of character and which is shown as extending on the inside of the span or bow *A*, the most conspicuous outline of the design, and as running 20 thence without seam or break of any kind to

mar or disturb its perfect evenness onto the divergent and ornamental lateral but different-appearing branches *b* and *c* at the base of the bow or arch *A*—that is to say, the design is marked and noticeable, especially by reason of the unbroken surface *a*, running, first, down within the bow *A* and then spreading in different directions onto the branches *b* and *c* and covering as well the outer surfaces of the divergent somewhat leaf-like formations *d* on 35 the branch *c*, thus sustaining the singleness or oneness of the design throughout. The otherwise smooth surface of the branches *b* is relieved by fine dots or spots *g*, sparingly scattered over the same. 40

What I claim is—

The design for a mounting for eyeglasses, substantially as herein shown and described.

Witness my hand to the foregoing specification this 22d day of March, 1899.

GEORGE A. SQUIER.

Witnesses:

H. E. MUDRA,
R. B. MOSER.
